UNITED STATES PATENT OFFICE.

JOHN G. MARVIN, OF MARION, INDIANA.

STORM-WINDOW.

1,321,224.

Specification of Letters Patent. Patented Nov. 11, 1919.

Application filed February 9, 1918. Serial No. 216,255.

To all whom it may concern:

Be it known that I, JOHN G. MARVIN, a citizen of the United States, residing at Marion, in the county of Grant and State of Indiana, have invented a new and useful 5 Storm-Window, of which the following is a specification.

This invention relates to a storm window intended for use principally on street cars, 10 automobiles, and other vehicles of transportation.

The invention contemplates a window which can be reversed for the purpose of cleaning; and also the provision of means 15 for draining water or moisture from the window and discharging the same outside of the vehicle or structure to which the window is attached.

A further object within the contemplation of the invention is the provision of means for preventing rain, snow and dust being driven through the openings about the window.

A still further object contemplated by the 25 invention is the provision of a simple, durable, and efficient window.

With the foregoing and other objects in view which will appear as the description proceeds, the invention resides in the combination and arrangement of parts and in the details of construction hereinafter described and claimed, it being understood that changes in the precise embodiment of the invention herein disclosed can be made 35 within the scope of what is claimed without departing from the spirit of the invention.

A practical embodiment of the invention is shown in the accompanying drawing, wherein:—

40 Figure 1 is a rear elevation of a window constructed in accordance with the invention;

Fig. 2 is a central longitudinal section; Fig. 3 is a detail side elevation of the 45 sash.

Referring to the drawing by numerals of reference:—

In carrying out the invention there is provided a fixed main frame or casing 1, and to 50 the opposed faces of the edges defining the opening to the frame a weather strip 2 of sheet metal or the like is secured. This strip is formed with an inturned flange 2' about its periphery at the front face of the 55 window frame or casing, and the edge of the

flange is bent backwardly for the purpose of contacting the window sash to make a tight joint and exclude snow and rain.

Pivotedly hung on pins 3 to swing vertically within the casing 1 is an auxiliary frame 4 within which a sash 5 pivots horizontally on pins 6 which are positioned in alining sockets formed in the upper and lower bars of the frame 4 and the sash 5. When the frame 4 and the sash 5 are swung 65 inwardly to an open position on the pivots 3, the flange 2' no longer bears on the outer surface of the sash, and then the sash may be reversed on the pins 6. A glass or other transparent panel 7 is inserted in the sash 5, 70 the sides of the sash being slotted for the purpose of allowing insertion and removal of the panel. A strip 8 is fitted into the slot at each side of the sash for the purpose of retaining the panel in place and these strips 75 may be retained by yokes 9, preferably formed of sheet metal, which are pivoted as at 10 to the lower corner at each side of the sash.

A strip or keeper 11 is formed along the 80 inner edge of the lower transverse bar of the casing and acts with the flange 2' to form a channel, as seen most clearly in Fig. 2, for the collection of rain or moisture which may have accumulated on the sash 85 and gravitated therefrom. This collected moisture is discharged from the channel through a discharge opening 12 formed in the lower flange 2'.

Buttons 13 are pivotally secured to the 90 lower transverse bar of the frame 4 and, when swung to their vertical positions, their lower ends engage the front face of the strip 11 to lock the frame 4 against swinging on its pivots 3, and their upper ends engage the rear face of the lower transverse bar of the sash 5 to lock the sash releasably against pivotal movement when the frame 4 and the sash 5 are swung to an open position on the pivots 3. A handle 14 is also 95 provided on the lower transverse bar of the frame 4 by which the frame may be swung on its pivots 3 and which may be engaged by a suitable hook or fastener, not shown, which may be swung from the roof of the 105 vehicle for the purpose of retaining the window in opened position.

It will be noted that the flange 2' extends before the slot formed by the meeting of the frame 4 with the casing 1 and also the slot 110

formed by the meeting of the frame 4 with the sash 5, so that rain or snow may not be driven through such openings.

Having thus described the invention, what is claimed as new and sought by Letters Patent, is:—

1. In a device of the class described, a fixed main frame; an auxiliary frame within the main frame; a sash within the auxiliary frame; a weather strip surrounding the auxiliary frame and located between the frames, the strip being secured to the main frame and including a continuous flange extended across the joint between the sash and the auxiliary frame and engaging the outer surface of the sash; means for pivoting the auxiliary frame at one end to the fixed frame whereby the auxiliary frame may be swung to an open position, thereby to space the sash from the flange of the strip; and means for pivoting the sash, midway between its edges, to the auxiliary frame, whereby the sash may be reversed after the auxiliary frame has been swung to an open

position to space the sash from the flange of the strip.

2. A device of the class described, constructed as set forth in claim 1, and further characterized by the fact that the flange of the strip is provided with a keeper, a button being pivoted intermediate its ends to the auxiliary frame, the button projecting inwardly to overlap the sash and outwardly to engage the keeper, thereby to hold the auxiliary frame closed in the main frame, and to hold the sash releasably against reversal in the auxiliary frame when the auxiliary frame is swung to an open position to space the sash from the flange of the strip.

In testimony that I claim the foregoing as my own, I have hereto affixed my signature in the presence of two witnesses.

JOHN G. MARVIN.
